BEET PULLER SHARE

Frank N. Tonkinson, Longmont, Colo.

Application January 9, 1932. Serial No. 585,769

3 Claims. (Cl. 55—106)

This invention relates to beet puller shares, and has for its object the production of a simple and efficient puller share, which is constructed with a projecting or elongated narrow finger at the soil 5 penetrating end for the purpose of more efficient extracting the beets from the ground and also for producing a durable and efficient share.

Another object of this invention is the production of a simple and efficient reversible beet pulling share which is adapted to efficiently open up 10 the soil and facilitate the pulling of the beet by forcing the beet up between the converging ends of the pair of shares which are adapted to be used together.

15 A still further object of this invention is the construction of a simple and efficient beet pulling share which is simple in construction and comprises a minimum number of parts.

With these and other objects in view, this invention consists in certain novel constructions and arrangements of parts which will be herein-after fully described.

In the drawing:—

Figure 1 is a front elevation of the shares 25 shown in position upon a beet pulling machine, one of the shares being shown in section;

Figure 2 is a perspective view of my improved beet pulling share;

Figure 3 is a bottom plan view of the share; 30 Figure 4 is an end elevation of the share;

Figure 5 is an edge elevation of the share; and

Figure 6 is a plan view of a modified form of the invention wherein only one end of the share is provided with a soil-penetrating finger.

35 By referring to the drawing, it will be seen that 1 designates a conventional form of beet pulling machine which may be constructed in any suitable or desired manner, and which is provided with a pair of inwardly turned supporting arms 40 2 suspended from the frame 1, each supporting arm 2 being provided with a suitable connecting head shown in dotted lines and indicated by the numeral 3, and being secured by means of the fastening screws 4.

45 In carrying out the present invention, two shares as indicated in general by the numeral 5 are employed, one share being supported upon each arm 2, and the shares being so mounted upon the arms as to converge toward their rear ends and to be pitched at an angle to suit the convenience of the operator, preferably at an angle of approximately forty-five degrees pitch from the front to the rear of the shares.

50 Each share comprises an elongated body, as shown in the drawing, the body 5 being provided

along its inner edge and at each end, with a projecting tapering finger 6, each finger being provided upon the top thereof and at its extremity with a cutting beveled point 7, and upon the bottom thereof with diverging beveled portions 8 and 9, terminating in a lower cutting edge 10, as clearly shown in the drawing. The finger 6, in each instance, is preferably of an elongated narrow type and projects from the body at one side of a cutting face or blade 11 having a sharpened 65 edge extending transversely across the end of the body 5 diagonally from the finger. The body preferably extends substantially flat throughout the main portion of its length but has its end portions bowed rearwardly to cause the finger 6 and blade 11 at its lower end to readily enter the ground as the machine moves forwardly. In view of this particular structure the fingers of the two shares will enter the soil in advance of the blades 11 to form narrow trenches at opposite sides of a 70 row of beets, after which the blades which are in set-back relation to the fingers will slice their way into the soil and loosen the same around the beets. As the machine travels in a forward direction, the 75 beet will pass up between the converging shares 5 and be forced up out of the ground due to this movement and due to the loosening and breaking up of the soil as brought about by the forwardly extending narrow penetrating finger cooperating 80 with the laterally extending rearwardly inclined 85 blade 11, as described.

As shown in Figure 6, there is a modified form of the invention wherein the body 12 of the share is provided with a finger 13 similar to the finger 6, only at one end. In carrying out the invention, 90 the share may be constructed so as to provide a finger at both ends, or one end, of the share according to the desire of the manufacturer or operator. In the preferred embodiment however, it is preferable to provide the projecting fingers at each end of the share in order that the blades may be reversed provided one end should become worn.

It should be understood that certain detail changes in the mechanical construction may be 95 employed without departing from the spirit of the invention so long as these changes fall within the scope of the appended claims.

Having described the invention, what is claimed as new is:—

1. Beet pulling means comprising a frame including supporting elements spaced transversely from each other, and shares carried by said supporting elements, said shares extending upwardly at a rearward incline in converging relation towards their upper ends and each at its lower end 105 110

being provided with a straight transverse cutting edge extending at a rearward incline toward its outer end and an earth-penetrating finger projecting forwardly from the cutting edge at the 5 inner end thereof and terminating in a sharpened free end, the fingers and forward end portions of said shares being bowed downwardly and rearwardly for the full width of the share.

2. A beet pulling share comprising an elongated 10 metal plate having a finger projecting longitudinally thereof from one end at a side of the plate and sharpened at its free end, the adjacent end of the plate being straight cut from the inner end of the finger to the other side edge of the plate 15 and sharpened, said plate being flat for the major portion of its length, and the finger and adjacent end portion of the plate being bowed longitudinally to curve downwardly and rearwardly when the share is mounted in position for use.

3. A beet pulling share comprising an elongated plate adapted to be secured intermediate its length to a support and extend upwardly at a rearward incline, said plate having a finger extending from each end longitudinally thereof at 80 one side of the plate, ends of the plate between the fingers and other side edge of the plate being straight cut and extending diagonally in converging relation to each other to form blades spaced from the free ends of the fingers, the fingers and adjacent end portion of said plate being bowed longitudinally whereby when the share is mounted in position for use a selected end may be disposed lowermost and have at its lower end a 85 downwardly and rearwardly curved blade and 90 finger for progressively entering the ground.

FRANK N. TONKINSON.
